UNITED STATES PATENT OFFICE.

WINFRED T. POWELL, OF ROCHESTER, NEW YORK, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,364,643.

Specification of Letters Patent.

Patented Jan. 4, 1921.

Application filed February 6, 1919. Serial No. 275,342.

To all whom it may concern:

Be it known that I, WINFRED T. POWELL, a citizen of the United States, residing at Rochester, in the county of Monroe, State 5 of New York, have invented certain new and useful Improvements in Telephone-Exchange Systems, of which the following is a full, clear, concise, and exact description.

This invention relates to machine switching telephone systems, and particularly to systems wherein special character service is provided.

The object of the invention is to provide means whereby a toll operator, upon answering the call of a subscriber whose line has been automatically extended to her position, may expeditiously identify such calling line.

Heretofore such an object has been accomplished through the use of a large amount of 20 complicated apparatus or through the use of a complete subscriber's multiple before the toll operator, whereby she might identify the calling line by making a revertive busy test.

25 The present invention is an improvement over such arrangements in that a calling line may be identified through a revertive busy test of the calling line made over an arrangement of apparatus, an organization 30 of circuits employing a number of testing points which is an extremely small percentage of the complete subscriber's multiple.

A feature of the invention is a plural bank of testing points connected to groups of subscribers' lines in such a manner that any one 35 of a large number of such lines may be tested by making connections separately to one testing point on each of the said banks. This and other features will appear in the 40 following description and appended claims.

In the drawing a subscriber's substation is represented at the left-hand upper corner connected to a line switch with an indicated extension to a toll operator's position at the 45 right-hand side of the drawing. In the lower portion of the left-hand side, the grouping arrangement of the calling lines is indicated and on the right-hand lower side the two groups of testing points are shown.

50 In general, the operation of this system is as follows:

The subscriber at station 1, by removing

his receiver from its hook, causes the line switch 2 to pick an idle trunk to a numerical switch 3, which he thereupon directively 55 actuates to extend his line to a toll operator's position, this invention being peculiarly adapted for use in connection with toll and long-distance traffic. Upon the extension of the subscriber's line to the toll operator's 60 position, a signal lamp 4 is caused to glow, whereupon the operator makes connection to the selected trunk associated with the signal 4 and receives the instructions of the calling subscriber. In order to verify the number 65 of the calling substation, the toll operator tests first a point in the bank of testing points 5 and then a point in the bank of the testing points 6, both of which points are associated with the calling line. If she receives the revertive busy test upon each 70 point which she tests she knows that he has given the number correctly and she thereupon proceeds to set up the connection in any ordinary and well-known manner. 75

When the subscriber at substation 1 removes his receiver from its hook, a circuit is established from ground, the upper inner armature and back contact of cut-off relay 7, to and through the apparatus of the substation 1, the innermost lower armature and back contact of cut-off relay 7, the winding of line relay 8 to battery and ground. The line relay 8 is energized and attracts its armature. A circuit is thereupon established 85 for the stepping magnet 9 of the line switch 2 extending from ground, the winding of magnet 9, brush 10, the normal terminal upon which it rests, the armature and contact of line relay 8, the armature and contact 90 of magnet 9, through a resistance 12 to battery and ground. Magnet 9 by including in its circuit its own armature and contact is self-interrupting. Upon the first actuation of magnet 9, the brush 10 is stepped off of 95 its normal contact and its circuit is removed from the control of the line relay, now extending from ground, the winding of magnet 9, the brush 10, the contacts over which it travels, the back contact and lowermost 100 armature of cut-off relay 7, the armature and contact of magnet 9, resistance 12 to battery and ground. Each time that magnet 9 attracts its armature to cause the step-

ping of the brushes, it interrupts its own circuit and therefore causes the continuous stepping of such brushes until they are stopped by the finding of an idle line. Such 5 idle lines are indicated by the presence of ground on the third from the bottom row of contacts.

We will assume that the last set of contacts is the first one leading to an idle line. 10 Therefore, when this set of contacts is reached a circuit is established from ground, the contact and armature of relay 13, brush 14, lower winding of cut-off relay 7, normal contact of the middle lower armature of relay 7, armature and contact of relay 8, armature and contact of magnet 9, resistance 12 to battery and ground. In this manner and 15 through the agency of resistance 12, the current delivered to magnet 9 when it retracts its armature after placing the brushes on the last set of contacts, is so reduced that it cannot again be energized. At the same time, cut-off relay 7 attracts its armatures, and 20 through the movement of its lowermost armature, insures the non-operation of magnet 9 by opening its circuit. Through the operation of the cut-off relay 7, the subscriber's line is cut off from the line relay and extended through the brushes 15 and 16 to the selected idle line. At the uppermost armature of cut-off relay 7, a circuit 25 is closed from battery and ground, through the winding of relay 13, the brush 17, the uppermost armature and contact of cut-off relay 7, the upper winding of cut-off relay 7, conductor 29, the primary winding of induction coil 18, to ground. Relay 13 becomes energized and opens the circuit for the lower winding of cut-off relay 7. Cut-off relay 7, 30 however, retains its armatures in their actuated position, due to the energization of its upper winding.

The idle line selected by the line switch extends to a numerical switch of any well-known type, which may be actuated through 45 the manipulation of a substation sending device indicated by 19. Only the parts of its circuits which form a part of the present invention are shown.

We will assume that the subscriber at 50 substation 1 manipulates his sending device 19 to set the brushes of the numerical switch 3 on to the terminals of a line leading to a recording toll operator's position. When switch 3 has thus been properly set, a circuit 55 is established from grounded battery, winding of relay 20, inner left-hand armature and contact of relay 11, the lower talking strand of the connection through the windings of polarized relay 23, the windings 60 and 51 of the repeating coil, the upper strand of the talking connection, the outer left-hand armature and contact of relay 11 to ground. Relay 20 becomes energized in this 65 circuit and attracts its armature whereby a

circuit is established for the lamp signal 4. The operator noticing the glowing of the lamp 4 inserts the plug 25 into the jack 26 associated with the selected line. A circuit is thereupon established from ground, the 70 winding of sleeve relay 27, the sleeve of the plug 25, the sleeve of the jack 26, through the winding of relay 11 to battery and ground. Relay 11 becomes energized in this circuit and through its right-hand armature 75 and contact locks up to the ground on the third conductor leading back through the upper winding of cut-off relay 7 to ground at the induction coil 18.

It will be noticed that the direction of 80 flow of current before the operator answered and just after she answered was from battery to the lower side of the talking conductor through the winding of the polarized relay 23, the upper strand of the talking conductor to ground. Relay 23 is not energized by current flowing in this direction. However, after the operator inserts the plug 25 into the jack 26, she actuates her listening key 28 to communicate with the calling subscriber at substation 1. This establishes a potential circuit for the reversal of current 85 in the line between the numerical switch and the operator's position whereby the relay 23 is energized at the proper time as will here- 90 inafter be more fully described.

Upon receiving the instructions of the subscriber at substation 1 the operator requests 95 that his line number be given her. Assuming that the substation 1 is actually numbered 2244 and that he gives this number correctly to the operator, she may check it in the following manner.

First, however, it will be well to explain 100 that the subscribers' lines, assuming this to be a ten-thousand line exchange, are divided into groups of one hundred lines each, there being one hundred of such groups. A conductor such as 29 is multiplied at the proper point to the upper winding of cut-off relay 7 110 of every subscriber's line, the last two digits of whose number are 44. In like manner, the conductor 30 will be multiplied at the proper points to the cut-off relays of those lines whose last two digits are 45, and the 115 conductor 31 to the lines whose last two digits are 46. In this manner every line in a ten-thousand exchange is connected to some one of the testing points in the bank of testing points 6.

A conductor 32 is multiplied to the lower 120 middle armature of the cut-off relay 7 of each of those subscriber's lines, the first two digits of which are 22. In like manner the conductor 33 is multiplied to the armature of the relays of those lines, the first two digits of which are 21 and similarly, the conductor 125 34 is multiplied to the lines, the first two digits of which are 20. Thus every subscriber's line is made to appear at one of 130

the testing points in the bank of testing points 5. Hence, through the testing of two points, one in the bank 5 and one in the bank 6, any particular line may be checked 5 twice.

As to the manner in which this is done, the following description will suffice.

We have assumed that the calling substation 1 is numbered 2244. The operator 10 therefore touches the tip of her plug 35 to the testing point 22 in the bank 5. Since this testing point is connected by induction coil 52 and the conductor 32, to the winding of cut-off relay 7 individual to the calling 15 line 2244, a reverte 70 busy test will be established. Ground at the induction coil 52 will be extended through the testing point 22, the tip of the plug 35, the upper armature and back contact of relay 36, the winding 20 of relay 37, to battery and ground. Relay 37 is energized in this circuit and through its outer armature extends ground through the outer right-hand contacts of listening 25 key 28 to the winding of relay 38, battery and ground. Relay 38 in turn becomes energized and through the action of its armatures reverses the direction of the flow of current through the polarized relay 23 which becomes energized. Through the inner armature of relay 37 a reverte 75 busy tone from the source BZ is connected through the outer left-hand contacts of listening key 28 to the sleeve of the plug 25, the sleeve of the jack 26, the right-hand 30 armature and contact of relay 11, the brush 35 80 17 of the line switch 2, the uppermost armature and contact of cut-off relay 7, the upper winding of cut-off relay 7, the primary winding of induction coil 18 to ground. Through the actuation of polarized relay 23 a ground is placed upon the conductor 100 leading to brush 14 during the actuation of relay 37, thence through the lower winding of cut-off relay 7, conductor 32, to the primary winding of induction coil 52, to ground. The reverte 75 busy tone current flowing through the upper winding of cut-off relay 7 is induced into the lower winding through the closure of the circuit just 45 described and such busy tone is projected over the conductor 32, to the induction coil 52, and then into agency to the testing point 22. From there it travels through the tip of the plug 35, the upper armature and back 50 contact of relay 36, the conductor 39, the condenser 40, the operator's receiver 41, the winding 42 of the operator's induction coil, the inner right-hand contacts of the listening key 28, to the ground 43. Thus the 55 operator is notified that she is testing the point associated with the calling line.

If the calling line, however, had actually been numbered 2144, the polarized relay 23 would have been energized in the same manner through this test, but the busy tone

would not have been connected to the conductor 33 and communicated to the testing point 21. Hence the operator in testing the point 22 would have received no reverte 70 busy tone.

The operator now has knowledge of the fact that the first two digits of the calling line had at least been given correctly. In order to determine if the last two had been given correctly she tests the point 44 in the 75 bank 6. In the manner described, the reverte 80 busy tone is transmitted through the upper winding of the cut-off relay 7 connected with the calling subscriber's line to the primary winding of the induction coil 18. By testing the point 44 the reverte 85 busy tone is induced in a circuit including ground, the secondary winding of the induction coil 18, the testing point 44, the tip of the plug 35 and thence over the circuit including the operator's receiver hereinbefore described.

Suppose again that that calling subscriber's line had actually been 2245. When the tip of the plug 35 is touched to point 90 44, and the relay 37 energized, the reverte 95 busy tone would have been induced into the induction coil 55 instead of 18 and no tone would have been transmitted to the induction coil 18. Therefore the operator 95 would have heard no reverte 100 busy tone and would have known that the number had been given incorrectly.

A further check may be made by the operator in the following manner:

It is possible that another operator might be making a reverte 100 busy test on a line, say No. 3744, in which case a busy tone would be induced into the induction coil 18, as hereinbefore described, and transmitted 105 to the testing point 44 and this operator would have received it. If, however, she taps the testing point 44 with the tip of her plug 35 in a manner peculiarly her own, she may be sure that the reverte 110 busy tone which she is receiving is that propagated by her own cord circuit. If she leaves the tip of the plug 35 on the testing point 44 for a short interval and the other operator makes a similar test by rapidly tapping the 115 tip of her plug 35 on the testing point associated with the thirty-seventh hundred, in the back 5, this operator will hear the other operator's code and know that the busy test which she is receiving is not 120 propagated by her own cord circuit.

After these operations have been completed the toll operator may instruct the calling subscriber to hang up so that she may recall him when she had established 125 the toll connection or give him any other instructions which the traffic rules prescribe.

When the calling subscriber hangs up and the operator removes the plug 25 from the jack 26, the connection is disestablished 130

in any well-known manner which will not be described here since it forms no part of the present invention.

What is claimed is:

- 5 1. In a testing system, circuits, testing points, each said testing point being associated with a different plurality of said circuits and each said circuit being associated with a different plurality of testing points,
- 10 10. a source of busy tone with one of said circuits, and means for testing for said busy tone on said testing points associated with said circuit.
- 15 2. In a testing system, circuits, testing points, an induction coil associated with each testing point, each said induction coil being associated with a different plurality of said circuits and each said circuit being associated with a different plurality of said
- 20 20. induction coils, a source of busy tone, means for associating said busy tone with one of said circuits, and means for testing for said busy tone on said testing points associated with said circuit.
- 25 3. In a testing system, circuits, a relay individual to each said circuit, a winding on said relay for its initial actuation, a second winding on said relay for its subsequent actuation, a testing point associated with said
- 30 30. second winding, a testing point associated with said first winding upon the actuation of said relay, a source of tone, means responsive to the testing of any of said testing points for connecting said source of tone to said second winding, means responsive to
- 35 35. the testing of said testing point associated

with said second winding for rendering said tone audible and producing thereby a signal, and means responsive to the testing of said testing point associated with said first winding for inducing therein currents similar to those propagated by said source of tone which is connected to said second winding for rendering said tone audible and producing thereby a signal.

4. In a testing system, circuits, a relay individual to each said circuit, a winding on said relay for its initial actuation, a second winding on said relay for its subsequent actuation, an induction coil connected to said second winding, an induction coil connected to said first winding upon the actuation of said relay, a testing point associated with each said induction coil, a source of tone, means responsive to the testing of any of said testing points for connecting said source of tone to said second winding, means responsive to the testing of said testing point associated with said second winding for rendering said tone audible and producing thereby a signal, and means responsive to the testing of said testing point associated with said first winding for inducing therein currents similar to those propagated by said source of tone which is connected to said second winding for rendering said tone audible and producing thereby a signal.

In witness whereof I hereunto subscribe my name this 27th day of January, A. D. 1919.

WINFRED T. POWELL.
